CASING FOR SHOE MACHINES

Ernest Hope, Leicester, England, assignor to
United Shoe Machinery Corporation, Flemington, N. J., a corporation of New Jersey

Application January 2, 1948, Serial No. 330
In Great Britain February 28, 1947

4 Claims. (Cl. 112—258)

1

The present invention relates to shoe machines and more particularly to improvements in protective and ornamental cover structures for such machines. An example of a machine to which the present invention is applied is a sewing machine illustrated in United States Letters Patent No. 1,133,147, granted March 23, 1915, upon application of L. E. Johnson and E. Erickson.

One of the various objects of the present invention is to provide a novel arrangement of dust excluding covers or hoods for the head of a machine capable of use in the manufacture or repair of shoes, by which hoods the mechanisms of the machine are protected against entry of dust or foreign matter but yet can be readily exposed for convenient adjustment or for other purposes.

Accordingly, one of the several features of the invention resides in a shoe machine having a head frame for supporting the operating devices, a horizontal driving shaft and mechanisms connecting the driving shaft with the operating devices in which the upper portions and sides of said mechanisms are shrouded in a novel manner by a number of hood members hinged in side-by-side relation at the upper part of the head frame for independent movement into and out of surrounding relation to said mechanisms.

Other features of the invention include novel and improved constructions, arrangements and combinations of parts hereinafter described and claimed which, together with the advantages to be obtained, thereby will readily be understood from the following description taken in connection with the accompanying drawings in which:

Fig. 1 is a view in front elevation partly broken away of a machine embodying the features of the present invention;

Fig. 2 is a view in side elevation of the upper portion of the machine;

Fig. 3 is a plan view of the machine illustrated in Fig. 1; and

Fig. 4 is a separated fragmentary perspective view on an enlarged scale illustrating the hinge connections between the hoods and wall members.

The machine illustrated in the drawings is a curved hook needle shoe sewing machine similar in construction and in manner of operation to that disclosed in the Johnson and Erickson patent, above identified, and comprises a hollow main supporting column 10 on the top of which is secured a head frame corresponding to the base 20 described in said patent. This base is constructed with end frames 12 and 14 provided with bearings for a main horizontal sewing shaft

2

16 and suitable actuating mechanisms, parts of which are indicated at 18 to connect the sewing shaft with the operating or stitch forming devices of the machine.

5 The top face of the supporting column is substantially rectangular in cross section and secured to this face at either side thereof is an upstanding wall member 20 or 22, each of somewhat U shape to correspond with the top edge of the column. The wall members extend part way across the front of the machine head into close fitting relation with the end frames 12 and 14. At the rear of the machine the two wall members meet at 15 as illustrated in Fig. 4 to form a dust 10 excluding enclosure. The height to which the wall members rise from the top face of the column is sufficient to surround the lower part of the end frames 12, 14 and protect the actuating mechanisms below the sewing shaft while providing in the right-hand wall member 22 a semi-circular recess to admit the sewing shaft, which has at its right-hand end a hand wheel 24.

15 To provide a protective enclosure for the upper portions of the machine head and to form 20 with the end frames 12 and 14 separate compartments within which the actuating mechanisms for the stitch forming devices operate in accordance with this invention, the upper rear portions of the wall members 20 and 22 have hinged on them a series of three hoods 26, 28 and 30 which 25 cover said mechanisms while leaving an opening at the front through which the stitch forming devices project. The hoods lie in side-by-side relation across the width of the machine and overlap the upper edges of the wall members 20 and 22 and except for the front of hood 28 form continuations of the surfaces of the wall members with a substantially smooth configuration except for a slight rib projecting from the hoods along their lower edges. These hoods are 30 curved upwardly and forwardly from their hinges over the head frame of the machine and comprise a pair of left and right hoods and a central hood between them. The right and central hoods 28 and 30 are hinged for vertical swinging

35 movement to the right-hand wall member 22 and the left hood is hinged for horizontal swinging movement to the left-hand wall member 20. The hinge mounting for the right-hand hood comprises perforated lugs 32 on the inside of the wall member 22 and similar lugs 34 on the hood 30 through which passes a horizontal pin 36 shown in Fig. 4 in separated relation. The arrangement is such that when the hood 30 is in closed position the lugs lie inside the compartment formed by the hood 30 and the end frame 40

14. The upper part of a driving mechanism is enclosed in this right-hand compartment, including a driving pulley 38 and a belt 40 surrounding a pulley 42 at the foot of the column 10, which belt in turn is driven from a motor 44 inside the lower portion of the column. Pulley 38 and belt 40 are exposed when the hood 30 swings rearwardly about its hinge pin.

The center hood 28 is of inverted U section terminating at its forward edge just above the sewing point of the machine defined by a work support 46 and a presser foot 48 for clamping a shoe while being operated upon by a curved hook needle 50 and others of the stitch forming devices. The hood 28 is hinged in a manner similar to that of the hood 30 on two perforated lugs 52 at the inside of the right-hand wall member 22 and two similar lugs 53 extending inwardly from the lower edge of the hood 28, through which lugs passes the pin 36 also forming a part of the hinge for the right-hand hood. Upon swinging the center hood 28 rearwardly the main actuating mechanisms for the stitch forming devices are exposed. When swung into place the hood 28 is supported along its forward edge by a face 54 on the end frame 14 just above the sewing point and the left-hand edge of the hood 28 is in the form of a vertical flange 59 engaging the right-hand face of the hood 26.

The left-hand hood 26 and the left-hand wall member 20 practically enclose the left-hand portion of the mechanism in the machine head and fit closely with the end frame 12. The hood 26 along its left edge has a vertical portion extending from the wall member 20 upwardly over the top of the compartment formed between the end frame 12 and the hood 26. The right-hand edge of the hood 26 abuts the flange 59 of the center hood 28, thus excluding dust or other foreign matter from this part of the machine.

On account of the shape of the left-hand hood 26 made necessary by its close surrounding relation to laterally projecting parts and mechanism at the left side of the machine it cannot be swung rearwardly and vertically about a horizontal axis. Accordingly, the left hood 26 is mounted on a vertical axis to swing horizontally and is provided along its rear inner portion with a lug 56 from which extends downwardly a vertical spindle 58. The spindle 58 is rotatably mounted in inwardly projecting lugs 60 on the wall member 20. To restrain the left-hand hood from accidental movement away from the end frame 12 the left-hand vertical portion of the hood carries along its lower edge a short downwardly projecting pin 62 (see Fig. 1). The pin 62 is so positioned that when the hood 26 is closed it engages the inner surface of the wall member 20. To open the hood 26, the forward edge of the member is lifted sufficiently to raise the pin above the upper edge of the wall member 20, the spindle 58 being mounted loosely in the lugs 60 to allow the front of the hood 26 to be raised slightly.

The right-hand wall member 22 has along its rearward upper edge four slots 64 spaced apart the proper distance to receive the lugs 34 and 53. When the center and right hoods are swung rearwardly, the engagement of the lugs 34 and 53 with the bottoms of the slots 64 limits the rearward movement of the hoods and holds them open in a convenient vertical position.

The three hoods 26, 28 and 30 when in closed position provide a substantially complete cover for the actuating mechanisms of the machine and any one of the hoods may be swung to open posi-

tion to give access to the different sets of mechanisms in the machine independently of the other two without exposing the other mechanisms. This result is particularly obtained from the arrangement of the end frames 12 and 14, dividing the machine more or less into compartments within which the different sets of mechanisms operate.

The nature and scope of the invention having been indicated and a particular embodiment having been disclosed, what is claimed is:

1. A shoe machine having a hollow main supporting column, operating devices, a head frame for the operating devices carried by the supporting column and constructed with end members, a horizontal main shaft in the said frame extending from side to side of the column, actuating mechanisms separated by the end frame members connecting the main shaft with the operating devices, and a wall member rising from the supporting column and surrounding the lower part of the head frame, in combination with a series of hoods hinged in side-by-side relation on the upper part of the wall member for independent swinging movement to form with the end frame members separate compartments for the actuating mechanisms for the operating devices.

2. A shoe machine having a hollow main supporting column, operating devices, a head frame for the operating devices carried by the supporting column and constructed with end members, a horizontal main shaft in the said frame extending from side to side of the column, actuating mechanism separated by the end frame members connecting the main shaft with the operating devices, and a wall member rising from the supporting column and surrounding the lower part of the head frame, in combination with a series of hoods, a horizontal hinge mounting for certain of the hood members to enable vertical swinging movement toward and from surrounding relation to the upper portions of the actuating mechanisms and a vertical hinge mounting to enable the hood member at one end of the main shaft to swing horizontally toward and from surrounding relation to one of said mechanisms.

3. A shoe sewing machine having a main supporting column, stitch forming devices disposed to operate on work presented at the front of the machine, a head frame for the stitch forming devices carried by the supporting column and constructed with end members, a horizontal sewing shaft in the head frame extending from side to side of the column for actuating the stitch forming devices, wall members rising from the supporting column and surrounding the lower part of the head frame, a hand wheel at one end of the sewing shaft projecting from one of the wall members, mechanisms for actuating and driving the sewing shaft including a pulley and a belt at the side of the head frame member with the hand wheel, in combination with a series of hood members hinged in side-by-side relation on the upper part of the wall member for independent swinging movement toward and from surrounding relation to the actuating and driving mechanisms to form separate compartments with the end frames for said mechanisms.

4. A shoe sewing machine having a main supporting column, stitch forming devices disposed to operate on work presented at the front of the machine, a head frame for the stitch forming devices carried by the supporting column and constructed with end members, a horizontal sewing shaft in the head frame extending from side to side of the column for actuating the stitch forming devices, wall members rising from the supporting column and surrounding the lower part of the head frame, a hand wheel at one end of the sewing shaft projecting from one of the wall members, mechanisms for actuating and driving the sewing shaft including a pulley and a belt at the side of the head frame member with the hand wheel, in combination with a series of hood members hinged in side-by-side relation on the upper part of the wall member for independent swinging movement toward and from surrounding relation to the actuating and driving mechanisms to form separate compartments with the end frames for said mechanisms.

70 75 76

side of the column for actuating the stitch forming devices, wall members rising from the supporting column and surrounding the lower part of the head frame, a hand wheel at one end of the sewing shaft projecting from one of the wall members, mechanisms for actuating and driving the sewing shaft including a pulley and a belt at the side of the head frame member with the hand wheel, in combination with a hood member hinged on the upper part of the wall member for vertical swinging movement toward and from surrounding relation to the driving mechanism, a second hood member hinged on the upper part of the wall member in side-by-side relation to the first-mentioned hood member for vertical swinging movement toward and from surrounding relation to the upper portions of the actuating mech-

anism centrally of the sewing shaft and a third hood member mounted upon a vertical hinge at the end of the sewing shaft opposite the hand wheel to swing horizontally toward and from surrounding relation to the upper portions of the actuating mechanism at said end of the sewing shaft opposite the hand wheel.
